UNITED STATES PATENT OFFICE.

WILLIAM J. MEE AND HARLEY A. TULLIS, OF HOLLYWOOD, CALIFORNIA; SAID MEE
ASSIGNOR TO CURTIS C. BENEDICT, OF LOS ANGELES, CALIFORNIA.

ATTACHMENT FOR PRINTING PRESSES.

Application filed November 24, 1925. Serial No. 71,094.

This invention is an improvement in printing cylinder presses.

An object of the invention is to provide a construction which may be embodied upon 5 printing cylinder presses of conventional construction, which will cause the printed paper as it is delivered from the press to become perforated, scored, slitted or crimped. Heretofore in so far as we are aware there 10 is no construction for perforating, scoring, slitting or crimping the paper as it is delivered from the press. Usually the paper is first printed and is delivered from the press to the jogging board. If it is desired to 15 form the paper, such as by perforating, scoring, etc., it is necessary to remove the paper on the jogging board and feed it through a separate machine. This is disadvantageous in that it usually requires hand feeding to 20 the machine and takes a considerable length of time. By the improved construction, which is in the form of an attachment for the conventional cylinder press, this second 25 operation is eliminated, namely, of feeding the paper to a perforating machine, and the paper is perforated before it is completely delivered from the press to the jogging board.

Another object of the invention is to provide 30 an attachment for cylinder presses which can be readily applied and which can easily accomplish any of the above mentioned operations, or can be disengaged entirely so that it will not deform the paper.

With the foregoing and other objects in view which will be made manifest in the following detailed description and specifically pointed out in the appended claims, reference is had to the accompanying drawings 40 for an illustrative embodiment of the invention, wherein:

Figure 1 is a top plan view of a portion of a cylinder press on which the attachment has been mounted,

Fig. 2 is a vertical section taken substantially on the line 2-2 of Fig. 1,

Fig. 3 is a vertical section taken on the line 3-3 of Fig. 1,

Fig. 4 is a vertical section taken on the line 4-4 of Fig. 1, and

Fig. 5 is a perspective view of the attachment.

Referring to the accompanying drawings wherein similar reference characters designate similar parts throughout, the cylinder

or roller of the press is indicated at 10 which is mounted for rotation upon the frame 11, which frame carries arms 12. The jogging board is indicated at 13 and the paper which has been printed and which is discharged 60 from the press is adapted to be stacked thereon.

On the conventional cylinder press there is a conveyor construction consisting of two shafts 14 and 15, the shaft 14 being rigidly 65 mounted between the arms 12, while the shaft 15 is mounted for rotation therebetween and is gearedly connected, as indicated at 16, to the cylinder or roller 10. On the stationary shaft 14 two or more pulleys 17 70 are loosely mounted so that they may rotate thereon, and on the rotary shaft 15 similar pulleys 18 are rigidly secured. On the conventional printing press endless rubber belts 75 pass over these pulleys and thus form conveyors for conveying the printed sheet of paper from the cylinder 10 to the jogging board.

The attachment consists of two side members 20 and 21, which have slots 22 extending upwardly therein from their bottom edges and which are adapted to receive the shafts 14 and 15. Lower shafts 23 and 24 have their ends rotatably mounted in these side members and are arranged in horizontal alignment between the slots 22. Slots 25 extend downwardly in the side members 20 and 21 from their upper edges and slidably receive blocks 26 which are arranged vertically above the lower shafts 23 and 24. Upper shafts 27 and 28 have their ends rotatably mounted in the blocks 26 and accordingly are arranged vertically above their corresponding lower shafts 23 and 24 respectively. The blocks 26 have threaded stems 85 secured thereto which extend through bridge pieces 30 and are provided with wing nuts 31 and lock nuts 32, so that the blocks can be raised and lowered and blocked in such adjusted positions, thus raising or lowering the shafts 27 and 28 with respect to the lower shafts. On the shafts 23 and 27 which are those disposed most adjacent the cylinder 10, there are arranged one or more sets of perforating or deforming rollers, 105 such as is indicated at 33. As shown in Fig. 3 the upper rollers which are on the shaft 27 constitute the male rollers having projections thereon so as to perforate the paper. The lower roller which is on the shaft 23 110

may be considered as the female roller and is complementary to the upper roller on the shaft 27. These rollers are preferably split so that they can be readily removed from the shafts 23 and 27 in order that other types of rollers may replace them. It will be readily understood that the particular form of the rollers on the shafts 23 and 27 is immaterial and can be varied. While the roller is illustrated as being a perforating roller, other rollers can be substituted, which will score, slit or crimp. Because of the fact that the rollers are split, they are adjustable along the length of their respective shafts, so that the perforating, scoring, slitting or crimping can take place at any point desirable on the paper delivered from the press.

In order to prevent the paper as it passes through the deforming rollers on the shafts 23 and 27 from curling around the upper or male roller, there is provided a plurality of guards or strippers. Two rods 34 are mounted between the side members 20 and 21, one of these rods being arranged forwardly of the shafts 23 and 27, while the other rod is arranged rearwardly of the shafts 24 and 28. The guards or strippers are indicated at 35 and have their ends fastened to these rods. They have slots formed in them so that the blades of the male deforming rollers can pass through them and engage their respective female rollers. It will be readily appreciated that the paper as it is discharged or delivered from the cylinder 10 passes beneath the strippers or guards 35, and the strippers prevent it from curling around or rolling around with the male deforming rollers.

When the paper passes through the deforming rollers, fibers will be struck out of its plane or project above its surface, and it is desired to smooth down or flatten these rough projecting fibers. Consequently, on the shafts 24 and 28 there are mounted smoothing rollers 36 and these rollers have smooth or flat peripheral surfaces, so that when they roll one upon the other with the paper passing between them, the projecting fibers will be flattened and smoothed. The guards or strippers 35 are bifurcated, as indicated at 37, so that the smoothing or flattening rollers may engage each other through the strippers.

Adjacent the side members 21, the shafts 23, 27, 24 and 28 are provided with gears 38. The gears on the shafts 24 and 28 are adapted to mesh with each other when the blocks 26 are in their lowered positions. In a similar manner the gears 38 on the shafts 23 and 27 are adapted to mesh when the blocks 26 on the shaft 27 are in their lowered positions. A pinion 39 is mounted on the side member 21 and meshes with the gears on shafts 23 and 24, which gears are somewhat wider or thicker than the gears

38 on the shafts 27 and 28. A pinion 40 is also mounted on the side member 21 and is adapted to mesh with the gear 38 on the shaft 23. By this gear construction it will be noted that if the pinion 40 is rotated, the shafts 23 and 27 will be caused to rotate in opposite directions so that the rollers thereon will cooperate to move the paper toward the jogging board. The shafts 24 and 28 are also caused to be rotated in the same directions as the shafts 23 and 27.

In applying the attachment to the printing press, two bushings are mounted on the rotary shaft 15 adjacent the arms 12, and rigid with one of these bushings is a gear 41. We find it desirable to remove the endless rubber belts on the pulleys 17 and 18, and replace these rubber belts by coil springs, indicated at 42, which have their ends connected and thus form an endless belt passing over these pulleys. When the attachment is applied, it rests on the shafts 14 and 15 with the side members 20 and 21 fitting just within the arms 12. The bushings on the shaft 15 rotate within the slots 22 which receive the shaft 15, and the pinion 40 on the side member 21 meshes with the gear 41 on the shaft 15, so that the various shafts 23, 24, 27 and 28 are driven by the shaft 15 and also the endless belts 42 are driven by the shaft 15. The construction of the parts is so arranged that the peripheral speed of the various rollers on the shafts 23, 24, 27 and 28 is the same speed as that of the endless belts 42, so that there will be no buckling or tearing of the paper as it passes through the attachment.

From the above described construction, it will be readily appreciated that an attachment for cylindrical presses is provided, wherein the paper which has been printed on the press can be perforated, scored, slit, or crimped before it is delivered to the jogging board, so that all the necessary operations on the paper can be accomplished on the press. Furthermore, if it is not desired to perforate or otherwise deform the paper, the blocks 26 can be elevated, raising the shafts 27 and 28 and causing their gears to cease meshing with the gears 38 on the lower shafts; or if desired, the complete attachment can be easily and quickly removed by lifting it from between the arms 12 as by handles 43.

It will be understood that various changes in the detail of construction may be made without departing from the spirit or scope of the invention as defined by the appended claims.

We claim:

1. An attachment for printing presses having a pair of parallel shafts, one of which is driven by the press and having pulleys on the shafts over which endless belts pass constituting a conveyor, said attachment

comprising two side members having recesses to receive said shafts so that the side members may rest thereon, two vertically aligned shafts having their ends rotatably mounted upon said side members, complementary paper deforming rolls mounted upon the vertically aligned shafts adapted to deform the paper as it passes over the conveyor from the printing press, and means for rotating 10 said vertically aligned shafts.

2. An attachment for printing presses having a pair of parallel shafts, one of which is driven by the press and having pulleys on the shafts over which endless belts pass constituting a conveyor, said attachment comprising two side members having recesses to receive said shafts so that the side members may rest thereon, two vertically aligned shafts having their ends rotatably mounted 15 upon said side members, complementary paper deforming rolls mounted upon the vertically aligned shafts adapted to deform the paper as it passes over the conveyor from the printing press, said vertically aligned 20 shafts being geared together, and means for driving them by the driven shaft of the first mentioned parallel shafts.

3. An attachment for printing presses having a pair of parallel shafts, one of which is driven by the press and having pulleys on the shafts over which endless belts pass constituting a conveyor, said attachment comprising two side members having recesses to receive said shafts so that the side members may rest thereon, two vertically aligned shafts having their ends rotatably mounted upon said side members, complementary paper deforming rolls mounted upon the vertically aligned shafts adapted to deform 35 the paper as it passes over the conveyor from the printing press, means for rotating said vertically aligned shafts, rods connecting the side members, one rod being located in front of the vertically aligned shafts and 40 the other behind them, and strippers having their ends connected to said rods and having intermediate portions adjacent the rolls for preventing the paper from sticking to the 45 rolls.

4. An attachment for printing presses having a pair of parallel shafts, one of which is driven by the press and having pulleys on the shafts over which endless belts pass constituting a conveyor, said attachment comprising two side members having recesses to receive said shafts so that the side members may rest thereon, two vertically aligned shafts having their ends rotatably mounted upon said side members, complementary 55 paper deforming rolls mounted upon the vertically aligned shafts adapted to deform the paper as it passes over the conveyor from the printing press, means for rotating said vertically aligned shafts, rods connecting the 60 side members, one rod being located in front

of the vertically aligned shafts and the other behind them, and strippers having their ends connected to said rods and having intermediate portions adjacent the rolls for preventing the paper from sticking to the rolls, said 70 rolls and strippers being laterally adjustable.

5. An attachment for printing presses having a pair of parallel shafts, one of which is driven by the press and having pulleys 75 on the shafts over which endless belts pass constituting a conveyor, said attachment comprising two side members having recesses to receive said shafts so that the side members may rest thereon, two vertically aligned 80 shafts having their ends rotatably mounted upon said side members, complementary paper deforming rolls mounted upon the vertically aligned shafts adapted to deform the paper as it passes over the conveyor 85 from the printing press, a second pair of vertically aligned shafts having their ends rotatably mounted upon the side members, smoothing rolls mounted upon said second pair of shafts adapted to smooth the paper 90 after it passes from between the paper deforming rolls, and means for driving all of said vertically aligned shafts.

6. An attachment for printing presses having a pair of parallel shafts, one of which is driven by the press and having pulleys 95 on the shafts over which endless belts pass constituting a conveyor, said attachment comprising two side members having recesses to receive said shafts so that the side members may rest thereon, two vertically aligned shafts having their ends rotatably mounted upon said side members, complementary paper deforming rolls mounted upon the vertically aligned shafts adapted to 100 deform the paper as it passes over the conveyor from the printing press, a second pair of vertically aligned shafts having their ends rotatably mounted upon the side members, smoothing rolls mounted upon said second pair of shafts adapted to smooth the paper 105 after it passes from between the paper deforming rolls, all of said vertically aligned shafts being gearedly connected together, 110 and means for driving them off from the driven shaft of the first mentioned pair of parallel shafts.

7. An attachment for printing presses having a pair of parallel shafts, one of which is driven by the press and having pulleys 115 on the shafts over which endless belts pass constituting a conveyor, said attachment comprising two side members having recesses to receive said shafts so that the side members may rest thereon, two vertically aligned shafts having their ends rotatably mounted upon said side members, complementary paper deforming rolls mounted upon the vertically aligned shafts 120 adapted to deform the paper as it passes 125

130

over the conveyor from the printing press, a second pair of vertically aligned shafts having their ends rotatably mounted upon the side members, smoothing rolls mounted upon said second pair of shafts adapted to smooth the paper after it passes from between the paper deforming rolls, means for driving all of said vertically aligned shafts, rods connecting the side members, one rod being located forwardly of the first mentioned pair of vertically aligned shafts and the other being located behind the second pair of vertically aligned shafts, and strippers having their ends fastened to said rods and having openings therethrough through which the rolls may engage each other, said strippers serving to prevent the paper from sticking to the rolls, said rolls and strippers being laterally adjustable.

8. An attachment for printing presses having a pair of parallel shafts, one of which is driven by the press and having pulleys on the shafts over which endless belts pass constituting a conveyor, said attachment comprising two side members having recesses to receive said shafts so that the side members may rest thereon, two vertically aligned shafts having their ends rotatably mounted upon said side members, complementary paper deforming rolls mounted upon the vertically aligned shafts adapted to deform the paper as it passes over the conveyor from the printing press, a second pair of vertically aligned shafts having their ends rotatably mounted upon the side members, smoothing rolls mounted upon said second pair of shafts adapted to smooth the paper after it passes from between the paper deforming rolls, means for driving all of said vertically aligned shafts, rods connecting the side members, one rod being located forwardly of the first mentioned pair of

vertically aligned shafts and the other being located behind the second pair of vertically aligned shafts, and strippers having their ends fastened to said rods and having openings therethrough through which the rolls may engage each other, said strippers serving to prevent the paper from sticking to the rolls, said rolls and strippers being laterally adjustable.

9. An attachment for printing presses comprising two side members, two pairs of vertically aligned shafts rotatably mounted between the side members, one shaft of each pair being adjustable, paper deforming rolls mounted upon one pair of vertically aligned shafts, smoothing rolls mounted on the other pair of vertically aligned shafts, means for rotating said vertically aligned shafts, rods connecting the side members, and strippers having their ends connected to said rods and having openings therethrough through which the rolls may engage each other.

10. An attachment for printing presses comprising two side members, two pairs of vertically aligned shafts rotatably mounted between the side members, one shaft of each pair being adjustable, paper deforming rolls mounted upon one pair of vertically aligned shafts, smoothing rolls mounted on the other pair of vertically aligned shafts, means for rotating said vertically aligned shafts, rods connecting the side members, and strippers having their ends connected to said rods and having openings therethrough through which the rolls may engage each other, said rolls and strippers being laterally adjustable.

In testimony whereof we have signed our names to this specification.

WILLIAM J. MEE.
HARLEY A. TULLIS.
